UNITED STATES PATENT OFFICE.

CURT STILLE, OF WILMERSDORF, NEAR BERLIN, GERMANY.

RELAY FOR TELEPHONES.

1,099,406.

Specification of Letters Patent.

Patented June 9, 1914.

Application filed January 11, 1910. Serial No. 537,514.

To all whom it may concern:

Be it known that I, CURT STILLE, doctor of philosophy, of Wilmersdorf, Germany, a subject of the King of Prussia, and whose post-office address is 7 Lauenburgerstrasse, Wilmersdorf, near Berlin, Kingdom of Prussia, German Empire, have invented a new and useful Relay for Telephones, of which the following is a specification.

10 The present invention relates to relays for telephones and other weak current apparatus, and which, as proved by experiments, are distinguished by very high sensitivity. A relay of this kind is produced 15 by causing two coils having a contact resistance between them to move against one another in a strong magnetic field. One form of this relay is shown by way of example in the accompanying drawing of which—

20 Figure 1 is a section and Fig. 2 a side elevation.

25 *a* designates the poles of a magnet, the core of which is *b* and which is energized from any suitable source of current by 30 means of the coil *e*. In the space between the magnet poles are two rotary coils or spools *f* arranged in series, but wound in opposite directions. In the interior of each spool is a carbon block *g*. These carbon blocks are provided with cavities in their 35 opposed faces, and the space so formed is filled with small carbon balls or grains. In order to prevent these small carbon bodies from dropping out, a band or strip *i*, preferably of glass wool, is placed around the 40 carbon blocks. The return movement of the spools to their initial position can be effected by torsional means, such, for instance, as two suspending threads *h*. These threads are attached to the hooks *l* forming a bifilar suspension.

45 The operation of the relay is obvious from the drawing. Any weak current traversing the spools tends to adjust the magnetic axis of the spools coaxially with the direction of the constant magnetic field. Since, however, the spools are oppositely wound, they move against one another, thereby influencing the contact member which is located between the spools.

50 What I do claim as my invention, and de-

sire to secure by Letters Patent of the United States, is:—

1. In a relay for telephones and similar apparatus the combination with two rotatably suspended coils adapted to rotate in opposite directions toward each other, of a microphonic contact located within and influenced by the rotation of the coils, and means for opposing the rotation of the said coils, substantially as set forth. 55

2. In a relay for telephones and similar apparatus the combination with two rotatably suspended coils adapted to rotate in opposite directions toward each other, and an electro-magnet adapted to produce a strong magnetic field, of a microphonic contact located within and influenced by the rotation of the coils and torsional means opposing the rotation of the said coils, substantially as set forth. 65

3. In a relay for telephones and similar apparatus the combination with two rotatably suspended coils adapted to rotate in opposite directions under the influence of a magnetic field, carbon blocks located in the interior of said coils, carbon balls interposed between said blocks to form a microphonic contact, a strip fastening the blocks together, and torsional means opposing the rotation of the said coils, substantially as set forth. 75

4. In a relay for telephones and similar apparatus the combination with two rotatably suspended coils adapted to rotate in opposite directions under the influence of a magnetic field, carbon blocks located in the interior of said coils, carbon balls interposed between said blocks to form a microphonic contact, a strip fastening the blocks together, and torsional springs opposing the rotation of the said coils. 80

5. In a relay for telephones and similar apparatus, the combination with two rotatably suspended coils adapted to rotate in opposite directions under the influence of a magnetic field, devices located in the interior of said coils, means interposed between said devices to form a microphonic contact, and torsional means opposing the rotation of said coils. 95

6. In a relay for telephones and similar

apparatus, the combination with two rotatably suspended coils adapted to rotate in opposite directions under the influence of a magnetic field, blocks located in the interior of said coils, means interposed between said blocks to form a microphonic contact, means for fastening the blocks together and torsional means opposing the rotation of said coils.

10 7. In an electric relay, the combination of two rotatably suspended oppositely

wound coils, blocks within said coils, means interposed between said blocks to form a microphonic contact, and torsional means opposing the rotation of said coils.

15

In testimony whereof I have hereunto set my hand in presence of two subscribing witnesses.

CURT STILLE.
